ABSTRACT OF THE DISCLOSURE

A motor operated head and arm moving mechanism for toy figures such as dolls designed to give the head a rotary rocking motion and to cause the arms to move alternately up and down, the mechanism being adapted for combination, if desired, with leg moving means.

FIELD OF INVENTION

This mechanism may be regarded as a modification of that disclosed in applicants' continuation-in-part application Ser. No. 638,234, filed May 15, 1967, for Baby Doll Walking Mechanism, in that substantially the same motor and gear elements are used, with the addition of elements connecting the head and/or arms to the power assembly. Connections for moving the legs are omitted from the present case because they are fully set forth in the application just cited, but the possibility of full mechanization of the doll, with legs, arms and head all moving, will be apparent. The fittings which connect each arm to the mechanism are shown as being of the type covered by Gardel Patent No. 3,098,318, July 23, 1963, and the head moving means resembles that covered by Gardel and Gorsky Patent No. 3,230,666, Jan. 25, 1966.

SUMMARY

The mechanism comprises means designed for convenient installation in the torso of a doll or the like for coupling the head and/or arms to a source of motive power so that the head and/or arms can be moved in a predetermined manner and synchronism; specifically, the head is given a rotary rocking movement and the arms are moved alternately up and down in a motion which may be regarded as patting an object or substance in front of the doll. The driving connections are such that either the head or the arms can easily be made independent of the power source, so that most of the parts of the mechanism can be standardized and put together in various combinations depending on the movements desired in any particular line of dolls.

A practical embodiment of the invention is shown in the accompanying drawings in which:

FIG. 1 represents a vertical front-to-back section of a doll torso and the neck portion of the head, parts being shown in elevation and parts being broken away;

FIG. 2 represents a detail elevation from the line II—II of FIG. 1 showing the form and position of the arm-moving rocker;

FIG. 3 represents a detail horizontal section on the line III—III of FIG. 1 showing the connection between one arm and the torso and the arm-moving rocker;

FIG. 4 represents a detail vertical sectional view of one of the couplings;

FIG. 5 represents a horizontal section on the line V—V of FIG. 4;

FIG. 6 represents a detail vertical sectional view of another coupling;

FIG. 7 represents a horizontal section on the line VII—VII of FIG. 6, and

2

FIG. 8 is a wiring diagram.

Referring to the drawings, the doll torso 1 is provided with circular arm openings lying in substantially vertical or only slightly inclined (30° or less) planes, each arm 2 being formed with an annular groove 3 around its upper end and being snapped into its respective arm opening, as shown in FIG. 3, the arms being thus journaled for rotation in a generally forward and back or up and down direction. The upper end of each arm is open and provided with an annular flange 4 adapted to be gripped peripherally by inner and outer plates 5, 6, a disc 7 having an integral forwardly projecting lever 8 being pressed firmly against the plate 6 by a spring 9, all as clearly set forth in Gardel Patent No. 3,098,318, cited above.

The head and arm operating mechanism includes a gear train 10 between upper and lower horizontal plates 11, 12, and a motor M in a generally U-shaped bracket 13 attached to the upper plate 11. The bracket 13 is affixed, as by bolts or screws 14, to the inner wall 15 of the battery box 16, a layer of resilient material 17 being preferably interposed between the bracket 13 and wall 15 so that vibrations from the moving parts will not be transmitted to the doll torso. The battery box 16 (containing, for example, two battery cells B of a suitable size) is firmly secured in an opening in the back of the doll torso 1 and is provided with a removable cover 18 for inspection or replacement of the batteries. The wiring between the batteries and motor is conventional and is shown in the wiring diagram FIG. 8. The circuit is shown as including a manually operated switch 19, conveniently operated by a button or lever on the back of the doll torso or adjacent to the battery box, and the circuit may optionally include, in series with the switch 19, a gravity switch or magnetic switch 20, the location and purpose of which is described below.

One of the intermediate gears 21 has its hub formed to permit passage of the vertical drive shaft 22 which is journaled in openings in the plates 11 and 12, extending to a point below the plate 12 and passing through an opening 23 in the motor bracket 13. The lower end of the shaft 22 has fixed thereto a cam follower 24 in the form of a horizontally disposed lever having an elongated slot 25, and the shaft 26 of the last gear in the train has its lower end formed as a crank 27 which is engaged in said slot.

At a point above the gear train, the upper end of the shaft 22 is engaged in a coupling 28 which connects the shaft operatively with a drive shaft extension 29, said extension passing through an opening 30 in a bracket 31 mounted on the upper part of the battery box. The bracket 31 has an upper horizontal portion 32 a short distance below the neck opening of the torso 1 and provided with a slot 33 extending in a front to back direction. The bracket 31 also has a short downward extension 34 in front of the drive shaft extension 29 and the arm moving rocker 35 is pivoted thereto by the rivet 36.

The upper end of the drive shaft extension 29 is operatively engaged in a second coupling 37 similar to the coupling 28 but radially bored partway through at its middle to permit insertion of a stub shaft 38 having a head 39. Said stub shaft extends forwardly from the coupling into engagement with a hole 40 in the rocker 35 above its pivot point. The rocker 35 is also provided in each of its lateral extensions, with horizontal slots 41, each adapted to receive one of the levers 8 for operating the arms.

A head moving shaft 42, the lower end of which is engaged in the coupling 37, extends upward from said coupling and through a plug 43 in the neck portion of the head, the upper extension 44 of said shaft being journaled in the neck plug 43 and offset from the axis of the lower portion of shaft 42 so that rotation of said shaft

will give the head a rotary rocking motion. Actual rotation of the head is prevented by the engagement of the pin 45 (fixed in the plug 43) in the slot 33, the parts last described being functionally similar to corresponding parts in the mechanism of Patent No. 3,230,666, cited above.

The shaft couplings 28 and 37 are provided for convenience in assembly and installation of the mechanism, being simple, reliable and adaptable. Each comprises basically a cylindrical body axially bored to a diameter approximating that of the shafts to be coupled and radially slotted (as at 46) to receive the flattened ends (such as 47) of the shafts. Axial movement of each shaft relative to its couplings or other supports may be prevented in a customary manner by staking small lugs or projections wherever needed, as indicated at 48 in several places, with or without the provision of washers.

When the motor is operated, its power is transmitted through the gear train 10 to the crank 27 which reciprocates the follower 24 in a small arc and thus turns the drive shaft 22 and its upper extensions 29 and 42 in oscillations of the same extent. The forwardly extending end of the stub shaft 38, engaging the rocker 35, causes rocking movement thereof and the engagement of levers 8 in slots 41 translates the rocking movement into alternate up and down movement of the arms. The head moving shaft 42, acting through its offset extension 44, gives the head a slight rotary rocking movement without actually rotating it.

The actions just described can be combined, in a manner readily understood, with the walking movements achieved by the mechanism of copending application Ser. No. 638,234, filed May 15, 1967 (cited above), but a particularly interesting and appealing effect is obtained by controlling the circuit in part by a magnetic switch (which may be of the type disclosed in applicants' copending application Ser. No. 633,266, filed Apr. 24, 1967), mounted in the back or lower part of the torso 1. With such a switch in the back of the torso, the doll may be laid on its back on a support containing a metal plate (e.g., iron) so that the switch will close the circuit and cause the doll's head and arms to move as described above, in close simulation of a baby in the same position. When the magnetic switch is mounted in the lower part or seat of the torso, the doll may be placed in a "high chair" (having a metal plate in the seat) with the hands in a position to pat the tray, or in a simulated bathtub (with or without water but, again, provided with a metal plate) where the hands will pat the water, if any, in a most realistic simulation of a baby enjoying its bath.

It will be understood that various changes may be made in the form, construction and arrangement of the several parts without departing from the spirit and scope of the invention and hence we do not intend to be limited to the details shown or described herein except as the same are included in the claims or may be required by disclosures of the prior art.

What we claim is:

1. A doll part moving mechanism for installation in a doll torso having arms articulated thereto, said mechanism including a motor and gears, an arm moving lever operatively connected to each arm, a rocker engaging both said levers, a drive shaft, means connecting said

shaft to said rocker, an eccentric element connected to one of the gears, and a follower fixed to the drive shaft and operatively engaged with said eccentric element.

5 2. A mechanism according to claim 1 in which the motor is electric, and which includes a battery box and supports for said motor, gears, rocker and drive shaft, said supports being mounted on said battery box and said box being affixed to the doll torso.

10 3. A mechanism according to claim 1 in which the eccentric element is a crank on a gear shaft below the gear train and the means connecting the drive shaft to the rocker is an element projecting from the drive shaft above the gear train and motor.

15 4. A mechanism according to claim 1 in which a head is articulated to the torso and which includes means connecting said motor to said head for causing the head to move when the motor is operated.

20 5. A mechanism according to claim 1 in which a head is articulated to the torso and which includes a neck plug in the head, a drive shaft extension journaled in said plug and angularly offset from the axis of the drive shaft and means preventing rotation of the head.

25 6. A mechanism according to claim 1 in which the arm moving levers extend forwardly from the arms, the rocker is pivotally mounted for reciprocating movement in a substantially vertical plane and is provided with openings to receive said levers and the drive shaft extends vertically from a point below the gear train to a point at least as high as the rocker.

30 7. A mechanism according to claim 6 in which one of the gears is formed with an axially bored hub and the drive shaft is journaled in said bore.

35 8. A doll part moving mechanism installed in a doll torso having arms articulated thereto, said mechanism including an electric motor, means connecting said motor to said arms for causing the arms to move when the motor is operated, and a motor circuit which includes a magnetic switch enclosed within the doll torso, said switch being adapted to close the circuit when the switch is placed sufficiently close to a suitable metallic body.

40 9. A mechanism according to claim 8 in which the switch is installed in the back portion of the torso in a position to be closed when the dolls' back is placed close to a suitable metallic body.

45 10. A mechanism according to claim 8 in which the switch is installed in the seat portion of the torso in a position to be closed when the doll is seated close to a suitable metallic body.

11. A mechanism according to claim 10 in which the arm moving means is adapted to move the arms up and down in a patting motion.
